UNITED STATES PATENT OFFICE.

IRWIN W. PRETORIUS, OF CHICAGO, ILLINOIS.

LETTER-BOX.

1,369,125.

Specification of Letters Patent. Patented Feb. 22, 1921.

Application filed November 26, 1919. Serial No. 340,714.

To all whom it may concern:

Be it known that I, IRWIN W. PRETORIUS, a citizen of the United States, residing at Chicago, in the county of Cook and State 5 of Illinois, have invented certain new and useful Improvements in Letter-Boxes, of which the following is a specification.

This invention seeks to provide letter boxes for apartment houses and office buildings, or other structures in which the mail for a number of tenants is delivered at a station on the ground floor of the building, and in which the presence of mail will not be indicated to outsiders so that robbing of 10 the boxes will not be an easy matter. A specific object of the invention is to provide a mechanism which will permit the letter carrier to simultaneously open all the letter boxes and close the several boxes after depositing mail therein. A further object of 15 the invention is to provide letter boxes by which the several tenants may individually withdraw mail from the boxes assigned to them without disturbing any of the other 20 boxes, and the invention also seeks to attain the stated objects by mechanism which will be simple and compact and not apt to get out of order.

The invention is illustrated in the accompanying drawings, in which—

Figure 1 is a front elevation of a row of boxes provided with my improvements;

Fig. 2 is a rear elevation with parts broken away and in section;

Fig. 3 is a transverse section on the line 3—3 of Fig. 2.

In carrying out the invention, I employ a facing plate 1 which may be ornamented in any desired manner and will be free of 40 openings except those provided for the doors to the several letter boxes. The openings will preferably be rectangular and a main door 2 will be fitted in each opening so as to fit closely therein but capable of swinging 45 therefrom and the door may be mounted to swing in a horizontal plane or in a vertical plane as may be preferred, the present drawings showing the door connected at its lower end by hinges 3 to the face plate 50 so that it will swing in a vertical plane. Above each door will be provided a name plate, or bracket 4 adapted to hold a name plate, so that the several boxes may be 55 properly designated to identify the tenants to which they are assigned. Each door 2 is preferably in the form of an inverted U-

shaped bar or frame and within the said door a smaller auxiliary door 5 fits closely but is connected to the face plate by a hinge 6 so as to swing concentrically with the 60 larger door as will be readily understood. The several doors 2 are provided on their inner sides with hasps or keepers 7 which are engaged by bolts 8 on the smaller door so that when the box is locked the two doors 65 will swing together. The bolt 8 will conveniently be mounted in a lock casing 9 on the inner side of the smaller door and will be controlled by a lock 10, preferably of the tumbler type, and the key to which will 70 be furnished the tenant to whom the box is assigned.

Each larger door 2 will be provided on its inner side at its upper end with a keeper 11 to be engaged by a bolt 12 mounted on the 75 face plate 1 immediately above the door and housed within a casing 13 secured to the said face plate. The bolt will be normally projected into engagement with the keeper by a spring 14 housed within the casing and 80 playing between the upper closed end of the same and the upper end of the bolt, as shown in Fig. 2. The casing is provided with a slot 15 through which the stem of a knob 16 carried by the bolt passes to aid in 85 guiding the bolt in its movements and to facilitate its release in the manner to be described. Fulcrumed upon the inner side of the face plate, adjacent each lock casing 13, is an angle lever 17 or 18 which has one 90 arm 19 extending under the stem of the knob 16 and suitably recessed to firmly engage said stem. The other arm of the lever extends upwardly and is pivotally connected 95 to a rod 20 which extends the full length 95 of the row of boxes so that all the angle levers will be simultaneously operated. The lever 18 at one end of the row of boxes is provided with a third arm 21 which extends therefrom in alinement with the arm 19 100 and projects over a lock 22 which will preferably be of the tumbler type employing a rotatable barrel 23. On the inner end of the barrel 23, I secure a crank arm 24, the end of which is connected by a link 25 with the 105 free end of the lever arm 21.

Partitions 26 will be provided at the inner side of the face plate 1 so as to separate the several letter boxes and upon the inner face of the plate 1 adjacent each partition and 110 below the door opening is secured a leaf spring or presser 27 which has its free end

bearing upon the door 2 and tending to throw the door downward. A stop rod 28 extends through the entire row of boxes adjacent the lower edges of the several doors 5 and upon each door is secured a hook or bracket 29 which passes below the said stop rod and is adapted, when the door is swung to open position, to engage against the said rod so as to prevent excessive dropping of 10 the door and support it in position to be easily grasped by the operator to be returned to closed and locked position.

Below each door and on the outer face of the face plate 1, I provide a clip 30 in which 15 newspapers or similar pieces of mail may be placed and a bell 31 and a speaking tube 32 may be provided as is now the general custom.

It is thought the uses and advantages of 20 the device will be readily understood from what has been said. As will be observed upon reference to Fig. 1, when the doors are raised and the letter boxes closed there are no openings through which the mail may 25 be seen and, therefore, malicious persons will not be enabled to determine the presence of mail by a casual inspection. Moreover, the usual slot provided for the insertion of mail is omitted and the withdrawal 30 of mail through said slot by the use of a wire or other tool is prevented. The letter carrier will be provided with a master key controlling the lock 22 and by inserting said key and rotating the barrel 23 he will cause 35 the crank 22 to exert a pull upon the link 25 which will be transmitted through the arm 21 to the levers 17 and 18 so that the said levers will be rocked about their fulcrums and the bolts 12 lifted against the ten- 40 sion of the several springs 14 and withdrawn from the keepers 11. Immediately upon the release of the bolts from the keepers, the presser springs 27 will push the main doors 2, which for convenience may be denoted as 45 carrier doors, to the position shown in dotted lines in Fig. 3 so that the mail may be then inserted over the opened door and through the door opening into the proper box. The tenant's door 5 will remain locked 50 to the carrier's door and will swing outwardly with it as will be readily understood. After the mail has been deposited, the carriers' doors are pushed back into closed position and will be automatically retained by 55 the bolts 12, the carrier then withdrawing his key from the lock 22 and proceeding on his way. A tenant, desiring to withdraw his mail, will insert a key furnished him and controlling the lock 10 of the door to his 60 box and will manipulate the lock so as to withdraw the bolt 8 from the keeper 7

whereupon the door 5 may be pulled open and the mail withdrawn. Upon returning the door to closed position the bolt 8 will automatically reengage the keeper 7 and the 65 door will then remain closed until again opened by the tenant or the letter carrier.

It will be readily noted that my device is exceedingly simple in the construction and arrangement of its parts and will effectually guard the mail against withdrawal by unauthorized persons. Moreover, the insertion of the mail will be facilitated inasmuch as a larger opening than heretofore will be provided and a more bulky volume 75 of mail may be deposited at one time.

Having thus described the invention, what is claimed as new is:

1. The combination of a plurality of letter boxes each having a door opening in its 80 front side, of a carrier's door and a tenant's door mounted in the respective door openings for concentric movement, means for locking the tenants' doors, and means on the inside of the box for locking all the doors 85 in closed position, said means being operable to permit simultaneous opening of all the doors and to permit independent opening of the several tenants' doors.

2. The combination with a plurality of 90 compartments each having a main door, locking means common to all the main doors and controlling all of said main doors, and a supplemental door in each main door and controlled by an individual locking means. 95

3. The combination with a letter box having a door opening, of a carrier's door and a tenant's door mounted within said door opening for concentric movement, means for locking both doors in closed position, 100 and means independent of the first mentioned locking means for locking the tenant's door in closed position and permitting opening thereof without disturbing the carrier's door.

4. The combination with a plurality of compartments each having a carrier's door and a tenant's door mounted for concentric movement, locking means common to all of the carriers' doors and controlling all of said 110 carriers' doors, locking means for each tenant's door independent of the locking means for the carriers' doors, means for projecting both doors of each compartment to open position when the carrier locking means has 115 been released, a stop rod arranged adjacent the doors, and coacting stop members carried by certain of the doors and adapted to engage said stop rod when the doors are opened.

In testimony whereof I affix my signature,
IRWIN W. PRETORIUS. [L.S.]
